FUMIGANT-TIGHT FLEXIBLE CONTAINERS

Arnold H. Beede, Stamford, Conn., assignor to Electrolux Corporation, Old Greenwich, Conn., a corporation of Delaware

Application June 11, 1952, Serial No. 292,867

8 Claims. (Cl. 229—65)

My invention relates to containers, commonly known as garment bags, for storing and protecting clothing or the like.

One of the objects of my invention is to provide a container of this type into and from which garments readily may be introduced and removed through a suitable opening, together with means for providing a fumigant-tight seal for such opening.

Another object of my invention is to provide a garment bag, including a supporting frame which maintains the walls of the bag in spaced relation during use, which may be folded into a compact package for storage and shipment.

Further objects and advantages of my invention will be apparent from the following description considered in connection with the accompanying drawings, which form a part of this specification, and of which:

Fig. 1 is a perspective view of the container or garment bag in accordance with my invention with the opening opened for the reception or removal of garments;

Fig. 2 is a perspective view similar to Fig. 1, but with the opening closed;

Fig. 3 is an exploded view of certain parts of the container;

Fig. 4 is a cross-sectional view of the supporting frame of the container;

Fig. 5 is a cross-sectional view on an enlarged scale taken on the line 5—5 of Fig. 1;

Fig. 6 is a cross-sectional view on an enlarged scale showing a detail of construction of the frame; and

Fig. 7 is a view on an enlarged scale showing another detail of the construction of the frame.

Referring more particularly to Fig. 1, reference character 10 designates generally a container or envelope made of flexible material which is preferably transparent and impervious with respect to the fumigant gas which is employed to protect the contents of the envelope from damage by clothes moths or the like. The best and most common fumigant for this purpose is paradichlorobenzene. If this is the fumigant to be used, the container may be made of a film of polyvinyl alcohol, which is a clear transparent material substantially impervious to the passage therethrough of paradichlorobenzene gas. This envelope may be made of a single sheet of this material folded along the bottom edge 12, with the remaining side edges 14 and 16 and the top edge 18 secured together in any suitable manner so as to form a container having two side walls and front, rear and top walls.

In one of the side walls 20 there is formed an elongated opening 22 having any desired extent, but preferably about three quarters of the vertical extent of the side wall. Suitable means are provided for mechanically closing this opening, such as snap fasteners or a slide fastener 24. However, a slide fastener does not provide a fumigant-tight closure for the opening, inasmuch as the gas may pass between the mechanically interlocked fingers of the fastener, and thus escape from the container.

Adjacent and parallel to this opening the end wall of

2

the container is formed with an elongated pocket 26 which preferably extends the entire height of the end wall. This pocket is closed at the bottom and open at the top and receives therein an elongated strip 28, the upper end of which extends out of the pocket. As shown, this strip consists of relatively thin spring steel which is dished transversely (see Fig. 5) to render it substantially rigid with respect to twisting about an axis parallel to its lengthwise extent, while at the same time being flexible and easily bendable about an axis at right angles thereto. A hand grip member 30 may be secured to the upper end of the strip 28 and, as is shown more particularly in Fig. 5, this member is formed with an arcuate recess 32 for receiving the end of the dished strip, the member being secured to the strip by means of a rivet or the like 34.

Disposed within the upper part of the container is a distensible and collapsible frame designated generally by reference character 36. This frame includes a bar-like member 38 which extends centrally along the top wall of the container. Bar 38 may be made of sheet metal with the edges formed as flanges 39 in order to provide rigidity. Pivotally connected to this bar is a pair of frame members 40, the pivotal connection being shown more particularly in Fig. 6, where it will be seen that a portion 41 of flange 39 near the end of the bar 38 is curved upwardly to embrace the end of the frame member. As is clear from Fig. 3, these frame members may be folded together so as to occupy minimum space during storage.

Each frame member 40 is provided centrally with a projection 42 which is received in a recess 44 formed in the end of a spreader member 46. As is shown, this spreader is generally of triangular shape and is formed with a plurality of openings 48 adapted to receive the hooks 50 of coat hangers for supporting garments in the container.

The spreader is preferably made of sheet metal with two of its edges rolled over to form the recesses 44. Secured to the top of the spreader in any suitable manner, as by spot welding indicated by 52, is a stirrup-shaped member 54 within which is secured an internally threaded member or nut 56. As shown in Figs. 3, 4 and 7, lips 58 are crimped over from the stirrup member 54 in order to secure the nut 56 to the stirrup. The bar 38 is formed with a centrally located aperture 60. A threaded rod 62 formed with an eye at its outer end extends through a small opening formed in the top seam 18 of the flexible container and through the hole 60 in the bar 38 for threaded engagement with the threaded member 56. A hook 64 for supporting the entire container from a clothes pole or the like is connected to the eye of rod 62. Also, a rod 66 is connected to this eye and is formed at its opposite end with a rectangular shaped eye 68. Rod 66 has a length a little greater than half the length of bar 38.

It will be noted that the load resulting from clothes on hangers suspended from the openings 48 in spreader 46 is transmitted through the latter and through rod 62 directly to hook 64, without being applied to the frame members 40 or the bar 38. Consequently, these members and the bar may be of much lighter construction than would be necessary if they were required to carry this load.

Inasmuch as paradichlorobenzene gas is heavier than air, the crystals from which this gas sublimates should preferably be located near the top of the container in order to obtain as uniform as possible distribution of the gas therein. As shown in Figs. 1 and 2, one or more strips 70 are looped over one or both of the frames 40. Secured to each strip is a plurality of small bags or containers 72 which contain paradichlorobenzene crystals. These containers are made of a material which is pervious with respect to the gas, such as cloth. However, they may be also made of a transparent material which at the

same time is pervious to the gas, such as polyvinyl chloride. It is advantageous to use transparent material in order that the user may at all times observe the amount of crystals remaining in the bags 72.

The above-identified device is used as follows:

With the container in the condition shown in Fig. 1, clothing or other articles to be stored may be readily introduced thereinto through the opening 22. The clothing is preferably placed on hangers which may be suspended in the openings 48 in the spreader 46, as shown in Fig. 2. Additional articles, such as blankets or the like, may be folded and placed in the bottom of the container. Thereupon, the slide fastener 24 is manipulated to mechanically close the opening 22. However, as previously stated, this does not provide a gas-tight seal for the opening. In order to accomplish the provision of such a seal, the handle 30 at the upper end of the strip is grasped and rotated so as to roll up the material of the end wall 20, which includes the opening 22, around the strip, as is shown in Fig. 2. In order to retain the wall in this rolled up condition, the eye 68 of rod 66 is placed over the handle 30, thus preventing rotation of the strip. Due to the fact that the container itself is made of material which is impervious to the fumigant gas and the opening 22 is substantially completely sealed by rolling the wall 20 up around the strip 28, there is practically no loss whatsoever of fumigant and consequently clothing and the like may be stored for an indefinite period of time.

Even though it is the rolling up of the wall, rather than the closing of the slide fastener, which produces a gas-tight closure of the opening, provision of the slide fastener is desirable because, with an opening of the length required in a garment bag, difficulty might be experienced in properly rolling up the wall on both sides of the opening if the edges of the wall bounding the opening were not held together.

In order to remove a garment from the container, it is merely necessary to disengage the rod 66 from the strip, unroll the side wall 20 and open the slide fastener. Whenever the container is open, a certain amount of fumigant gas will escape and eventually all the crystals within the bags 72 will be used up. When this occurs, a new strip of material 70 with full bags 72 attached thereto may be hung over the frame members.

In order to collapse the supporting frame 36 for storing the container in a minimum space, the projections 42 may be withdrawn from the recesses 44 by slightly springing the frame members 40. Thereupon the spreader 46 may be turned through 90° so as to extend parallel to the bar 38 and the frame members 40 pivoted towards each other so that the entire frame lies in practically a single plane. The strip 28 may be withdrawn from the pocket 26 and the flexible material of the container folded around the frame member. The garment bag may then be packed in a suitable cardboard box or the like. Due to the fact that the strip may be bent about an axis transverse to its lengthwise extent, this strip may be curled up so as to extend around the inside of the box.

While I have shown and described one more or less specific embodiment of my invention, it is to be understood that this has been done for the purpose of illustration only and that my invention is not to be limited thereby, but is to be interpreted as broadly as the appended claims permit.

What I claim is:

1. A garment bag comprising a container made of flexible fumigant-impervious material having side walls and a closed top and bottom, a frame positioned in the top of the bag, one of said side walls extending outwardly beyond the frame and formed with an elongated longitudinal opening therein, means for releasably securing the opposite edges of said opening together, and means for rolling up the material of said container adjacent to and

including said opening to provide a fumigant tight seal therefor.

2. A garment bag comprising a container made of flexible fumigant-impervious material having side walls and a closed top and bottom, a frame positioned in the top of the bag, one of said side walls formed with an elongated opening therein, means for releasably securing the opposite edges of said opening together, and an elongated strip secured to the material of the container beyond the frame adjacent and substantially parallel to said opening and having one end free of said material and forming a handle portion, said strip being substantially rigid with respect to twisting about an axis parallel to its lengthwise extent and being rotatable by said handle portion about said axis of said strip to roll thereon said material adjacent to and including said opening to provide a fumigant tight seal therefor.

3. A garment bag comprising a container made of flexible fumigant-impervious material formed with an elongated opening in a wall thereof, means for releasably securing the opposite edges of said opening together, and an elongated resilient metal strip secured to the material of the container adjacent and substantially parallel to said opening and having one end free of said material and forming a handle portion, said strip being dished transversely to render it substantially rigid with respect to twisting about an axis parallel to its lengthwise extent, said strip being rotatable by said handle portion about said axis of said strip to roll thereon said material adjacent to and including said opening to provide a fumigant tight seal therefor.

4. A garment bag comprising a container made of flexible fumigant-impervious material formed with an elongated opening in a wall thereof, means for releasably securing the opposite edges of said opening together, an elongated strip secured to the material of the container adjacent and substantially parallel to said opening and having one end free of said material and forming a handle portion, said strip being substantially rigid with respect to twisting about an axis parallel to its lengthwise extent and being rotatable by said handle portion about said axis of said strip to roll thereon said material adjacent to and including said opening to provide a fumigant tight seal therefor, and means carried by said container and engageable with said handle portion for restraining rotation of said strip.

5. A garment bag comprising a container made of flexible fumigant-impervious material formed with an elongated opening in a wall thereof, means for releasably securing the opposite edges of said opening together, an elongated pocket open at one end on said container adjacent and substantially parallel to said opening, and an elongated strip in said pocket with one end thereof extending out through the open end of said pocket to provide a handle portion, said strip being substantially rigid with respect to twisting about an axis parallel to its lengthwise extent and being rotatable by said handle portion about said axis to roll up the material adjacent to and including said opening to provide a fumigant tight seal therefor.

6. A garment bag comprising a container made of flexible fumigant-impervious material formed with an elongated opening in a wall thereof, means for releasably securing the opposite edges of said opening together, an elongated pocket open at one end on said container adjacent and substantially parallel to said opening, an elongated strip in said pocket with one end thereof extending out through the open end of the pocket and providing a handle portion, said strip being substantially rigid with respect to twisting about an axis parallel to its lengthwise extent and being rotatable by said handle portion about said axis to roll up the material adjacent to and including said opening to provide a fumigant tight seal therefor, and a member movably connected to

said container and engageable with said handle portion for restraining rotation of said strip.

7. A garment bag comprising a container having top, bottom and side walls made of flexible fumigant-tight material, a frame disposed within the upper part of said container for holding said side walls in spaced relationship, one of said side walls being formed with an elongated opening, means for releasably connecting opposite edges of said opening together, an elongated strip secured to the said one side wall adjacent and substantially parallel to said opening, said strip being rotatable about its lengthwise axis to roll up the material adjacent to and including said opening to provide a fumigant-tight seal therefor, a rod connected to said frame and having its outer end extending through said top wall, and a member movably secured to the outer end of said rod and securable to said strip to restrain rotation of the latter. 15

8. A garment bag comprising a container having top, bottom and side walls made of flexible fumigant-tight material, a frame disposed within the upper part of said container for holding said side walls in spaced relationship, one of said side walls being formed with an elongated opening, means for releasably connecting opposite edges of said opening together, an elongated pocket open 20

5

10

15

20

at its upper end on said one side wall adjacent and substantially parallel to said opening, an elongated strip in said pocket with the upper end thereof extending out through the open end of the pocket, said strip being rotatable to roll up the material adjacent to and including said opening to provide a fumigant-tight seal therefor, a rod connected to said frame and having its outer end extending through said top wall, and a member movably secured to the outer end of said rod and formed with an eye for receiving the upper end of said strip to restrain rotation of the strip.
